CLAIM

The ornamental design for a tablet computer, as shown and described.

DESCRIPTION

The present application is related to U.S. Design patent application Ser. No. 29/611,586, filed on Jul. 24, 2017, and entitled Open Laptop Computer, and to U.S. Design patent application Ser. No. 29/611,587, filed on Jul. 24, 2017, and entitled Closed Laptop Computer, the entire disclosures all of which are incorporated herein by reference.

FIG. 1 is a front perspective view of a tablet computer according to our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof; and,

FIG. 8 is a rear perspective view thereof.

The broken lines in the drawings depict portions of the tablet computer that form no part of the claimed design.
